UNITED STATES PATENT OFFICE.

ALEXANDER P. WHITE, OF CALDWELL, NEW JERSEY.

FIBROUS BUILDING MATERIAL.

1,281,453.

Specification of Letters Patent. Patented Oct. 15, 1918.

Application filed January 3, 1914. Serial No. 810,141.

To all whom it may concern:

Be it known that I, ALEXANDER P. WHITE, a citizen of the United States, residing at Caldwell, in the county of Essex and State 5 of New Jersey, have invented certain new and useful Improvements in Fibrous Building Material, of which the following is a specification.

This invention relates to a novel and practical building material available chiefly for lathing, although it may be used for other purposes in building construction.

To this end, the invention has for its object to provide an improved building material and to cheapen the cost of building construction, and primarily involves a novel manner of combining a fibrous corrugated sheet with stiffening and reinforcing materials in the various ways shown in the accompanying drawings, in which—

Figure 1 is a perspective view of one form of building material embodying the present invention.

Fig. 2 is a cross sectional view of the form 25 of construction illustrated in Fig. 1.

Fig. 3 is a view similar to Fig. 2 showing a modified form of construction.

Figs. 4 and 5, 6 and 7, 8 and 9, 10 and 11 are paired views respectively in plan and 30 section of various modifications of the invention as to the arrangement of the metallic members and the method of disposing the same for engagement by the plaster.

Figs. 12 and 13 are similar plan views of 35 additional modifications of the material.

Fig. 14 is a view similar to Fig. 3 illustrating an embodiment of the invention wherein the corrugated sheet and the metal elements seated therein are inclosed between 40 plain facing sheets which are imperforate throughout.

Like reference characters designate corresponding parts in the several figures of the drawings.

Referring to the conditions leading up to the present invention, it is well known that in the use of articles of this nature composed of metallic elements, as for example wire lath or expanded metal, there is an objection 45 to the liability of the metallic parts to corrode or rust. And accordingly, it is the purpose of the present invention to provide a building material wherein the metal parts are completely covered, as well as to provide a novel construction of building material which when used as a lath requires

much less plaster to form the wall thereof than is required by the usual woven wire and expanded metal fabrics. In the use of all-metal fabrics, much plaster is wasted or lost 60 by passing through the meshes of the fabric, and a heavier coat of plaster is necessary to make an even surface, and it is these objections particularly which are successfully met and overcome by a fibrous building material 65 constructed in accordance with the present invention.

The improved building material claimed herein, primarily includes a sheet of fibrous corrugated body material A, such for instance as a sheet of corrugated paper, combined with a flat facing sheet B of paper or other fibrous material, as shown in all of the figures of the drawings. Through the valleys formed by the corrugations, there are 70 placed reinforcing metal stringers or strands C, preferably consisting of steel rod lengths made of, say No. 10 gage steel wire which are spaced at suitable intervals, say four inches apart, and when cross rods are 75 combined with these main strands or rods, as hereinafter explained, the cross wires employed may be of a smaller gage, such as No. 18 gage steel rods.

According to the embodiment of the invention shown in Figs. 1 and 2 of the drawings, the corrugated body sheet A is illustrated as having the paper or equivalent facing sheet B glued or otherwise suitably fastened upon one side of the sheet, and by 85 reason of having a fastened union with the ridges of the corrugations becomes a permanent part of the body material and contributes to its stiffness and durability. Also, the facing sheet acts as a covering for the 90 grooves of the corrugations at one side of the sheet, and thereby holds in place the metallic members or rods C which are placed in any desired number in the grooves according to the requirements of the wall or ceiling to be 95 constructed.

In Fig. 3 of the drawings, there is shown the expedient of applying a facing sheet upon both sides of the corrugated sheet where it is desirable to obtain extra stiffness 105 and strength for the building material or form. The additional facing sheet in this modification is designated by the reference letter E, and in all other respects the construction and use of this form of the invention is the same as that illustrated in Figs. 1 and 2.

In this embodiment of the invention, the rod containing grooves covered by the facing sheet B permits the plaster or cementitious material to engage about the metallic members or rods so as to be permanently supported thereby when said material has set and hardened. This is accomplished in a practical manner by breaking up the body material A—B, A—B into a number of key 5 openings D disposed adjacent the longitudinal plane of the individual metallic members or rods, so that the plaster applied to the surface of the supporting body will press through the openings and about the rods C 10 in the manner indicated in Figs. 2 and 3 of the drawings.

According to the form of the invention shown in Figs. 4 and 5 of the drawings, the metallic members are shown in crossing relation, and at their points of crossing exposed to a considerable degree for direct engagement by the cementitious material. Referring to this form of the invention, it will be observed that the same includes in 20 addition to the main corrugated sheet A, the facing sheets B and E respectively upon opposite sides thereon and supplemental metallic members or rods F which are arranged in crossing relation to the rods C and 25 the grooves of the corrugated sheet, and are held directly on the ridges of the corrugations by the facing sheet B. In the plane of the point of crossing of the metallic members C and F, the facing sheet B is 30 provided with key openings G of cross-form, which provide an effective means of insuring the positive and permanent interlocking engagement between the plaster and the metallic members of the structure.

40 Substantially the same combination of features is involved in the forms shown in Figs. 6 and 7 of the drawings with the single exception that the key openings G' in this construction pierce both of the facing 45 sheets, thus rendering the material reversible and providing for a more extensive area of keying the plaster about the metallic members at their points of crossing. The same general idea of the modification shown 50 in Figs. 4 and 5 is preserved in the modification of Figs. 8 and 9, with the exception that in the latter form of construction, there may be employed comparatively stout metallic members or rods C, located in the 55 grooves of the corrugated sheet and employed without supplemental crossing rods or wires. Also, in this form of construction shown in Figs. 8 and 9, portions of each metallic member or rod are exposed 60 at intervals through key openings G" formed in one of the facing sheets and disposed longitudinally of the metallic member or rod.

In Figs. 10 and 11 of the drawings, is 65 shown a form of construction which is the

same in all respects as that of Figs. 8 and 9, with the exception that the key openings G' pierce both facing sheets and the intervening corrugated sheet.

Another method of exposing the metallic members or rods for direct engagement by the plaster is that shown in Fig. 12 wherein the main and supplemental metallic members C and F are employed, and each of which is exposed at 75 intervals through key openings G' and G" respectively in one or both of the opposing sheets, and in Fig. 13 is shown a form of the invention which illustrates how the key openings G' in one or both of the facing 80 sheets may be of elliptical or other design to expose the members at their points of crossing to a comparatively large area of the plaster or cementitious material.

In all of the embodiments of the invention 85 so far described, the metal, to some extent at least, is disposed for direct engagement by the cementitious material, but the principal objects of the invention may be attained by having imperforate facing sheets B' which 90 entirely cover and protect the metallic rods in the valleys of the corrugated body sheet as shown in Fig. 14 of the drawings. In this form of the invention the plaster will be applied directly to either side of the 95 material.

Furthermore, another feature of importance that may be embodied in the present invention is that of providing any desired number of corrugations of the body sheet 100 with cementitious fillings 8 placed in the valleys or grooves, and which when hardened and set adds to the strength of the material. See Figs. 1, 2, 3 and 5.

Also, it may be found preferable in carrying out the invention to treat the body material with a compound for the purpose of imparting waterproofing and fire-resisting characteristics thereto, as for example a compound consisting of a mixture of silicate 105 of soda and asphaltum or oxid of iron.

Various changes in the form, proportion, and minor details of construction may be resorted to without departing from the spirit or sacrificing any of the advantages 110 of the invention, or without departing from the scope of the appended claims.

I claim:

1. A building lath comprising a series of spaced apart metal stringers, a supporting body for the metal stringers consisting of a sinuous fibrous sheet having a multiplicity of contiguous corrugations, in the valleys of at least some of which corrugations the metal stringers are longitudinally seated, and a facing sheet united with the corrugated sheet and having openings communicating with valleys of the corrugations.

2. A building lath including a series of 130

- metallic stringers, and a supporting body therefor consisting of a sinuous sheet of fibrous material having a multiplicity of contiguous corrugations in the valleys of at least some of which corrugations the metallic stringers are longitudinally seated, and a facing sheet attached to the body sheet and provided with key openings exposing therethrough said metallic stringers.
3. A building lath including a series of metallic stringers, and a supporting body therefor consisting of a sinuous sheet of perforated fibrous material having contiguous corrugations in the valleys of at least some of which the metallic stringers are longitudinally seated, and a facing sheet united with the corrugated sheet and provided
- with key openings exposing through the same said metallic stringers.
4. A building lath consisting of a series of metallic stringers arranged in crossing relation, a supporting body therefor of fibrous material corrugated throughout, and a facing sheet secured upon said material over the metallic stringers, said supporting body having key openings exposing therethrough the metallic stringers at their points of crossing.
- In testimony whereof I hereunto affix my signature in the presence of two witnesses.
- ALEXANDER P. WHITE.
